BREECH OPERATING MECHANISM

Charles William Cochran, Jr., Aldan, Pa., assignor, by mesne assignments, to the United States of America as represented by the Secretary of the Navy

Application December 5, 1951, Serial No. 259,998

4 Claims. (Cl. 89—24)

1

The invention relates to improvements in breech mechanism for guns and more particularly to improved toggle spring breech operating mechanism for a gun equipped with a reciprocable breechblock.

An important object of the invention is to provide breech operating mechanism with means for assisting in the opening and closing of a reciprocable breechblock.

Another object of the invention is the provision of means oppositely biasing a reciprocable breechblock in its open and closed positions.

A further object is to provide toggle spring linkage oppositely biasing a reciprocable breechblock in its open and closed positions.

Other objects and advantages of the invention will become apparent during the course of the following detailed description, taken in connection with the accompanying drawing forming a part of this specification, and in which drawing:

Figs. 1 and 2 are central vertical longitudinal sectional views of the breech end of a gun and showing the reciprocable breechblock and its associated operating mechanism in closed and open positions, respectively.

In the drawing which for the purpose of illustration shows only a preferred embodiment of the invention and wherein similar reference characters denote corresponding parts throughout the views, the numeral 10 generally designates the breech end of a gun including a barrel portion 11 and a housing 12. Vertically slidably mounted in an upwardly and forwardly inclined guideway 13 for reciprocation between open and closed positions is a breechblock 14 which, in moving upwardly, becomes wedged against the base of a cartridge 15 in the gunbore 16.

Journalized transversely of the breech end of the gun and forwardly of the breechblock in its open position is a breech operating crankshaft 17 provided with a crank 18 for angular adjustment. Connected between the crankshaft 17 and breechblock 14 is toggle joint mechanism 19 adapted to translate angular oscillatory motion of the crankshaft into rectilinear reciprocatory motion of the breechblock between its open and closed positions. This toggle joint mechanism 19 includes a lever arm 20 fixed on the crankshaft and having its free end pivoted at 21 to one end of a link 22 whose opposite end is pivoted at 23 to a lug 24 projecting downwardly from the breechblock. Formed integrally with the lever arm 20 is a lateral projection 25 adapted to engage a rigid portion of the housing 12 upon movement of the toggle joint mechanism through its

2

extended dead-center position to a slightly buckled position in which the breechblock is closed, this toggle joint movement being imparted by clockwise rotation of the crankshaft as viewed in Figs. 1 and 2. By rotating the crankshaft 17 in a counterclockwise direction, the toggle joint is moved through its dead-center position into a collapsed position wherein the breechblock 14 is opened.

10 Connected between the crankshaft 17 and a pivot 26 mounted thereabove in the breech end of the gun is toggle spring linkage 27 biased for collapsing movement from a straightened position toward either one of the two buckled positions shown in Figs. 1 and 2, wherein the breechblock 14 is respectively closed and open. This toggle spring linkage 27 includes a lever arm 28 fixed on the crankshaft and having its free end pivoted at 29 to the rod end of a telescopic link 30 including relatively axially movable cylinder and rod portions 31, 32, the cylinder end portion 31 being pivoted to the gun breech at 26.

Encircling the rod portion 32 within the cylinder and bearing against a flange 33 on the rod 25 is an expansion coil spring 34 adapted to urge the cylinder and rod portions into axially extended relation for lengthening the link. The combined lengths of the lever arm 28 and the telescopic link 30 when axially extended is greater than the distance between the pivot 26 and crankshaft 17 whereby the spring 34 urges the toggle linkage 27 from its straightened position toward either one of its two buckled positions.

In the operation of the mechanism, as the breechblock 14 is opened, the lever arms 20, 28 35 swing until the toggle spring linkage 27 passes over its dead-center position whereupon the spring 34 assists in opening the breechblock completely and then biases it in the open position. Also, when the breechblock is being closed, the toggle spring 34 operates in a similar manner to close the breechblock and bias it in its closed position.

Various changes may be made in the form of invention herein shown and described without departing from the spirit of the invention or the scope of the following claims.

What is claimed is:

1. In a gun provided with a breechblock reciprocably slidable between closed and open positions, a breechblock operating crankshaft journaled in the breech end of the gun, a toggle joint connecting said crankshaft and breechblock for translating oscillatory crankshaft motion into reciprocatory breechblock motion between positions wherein said breechblock is opened and

closed respectively, and toggle spring linkage connecting said crankshaft and the breech end of the gun and biased for collapsing movement from a straightened position toward either one of two buckled positions, said breechblock being respectively open and closed when said toggle spring linkage is in one or the other of said buckled positions.

2. In a gun provided with a breechblock reciprocably slideable between closed and open positions, a breechblock operating crankshaft journaled in the breech end of the gun, a toggle joint connecting said crankshaft and breechblock for translating oscillatory crankshaft motion into reciprocatory breechblock motion between positions wherein said breechblock is opened and closed respectively, an abutment positioned for engagement by said toggle joint upon closing of said breechblock, and toggle spring linkage connecting said crankshaft and the breech end of the gun and biased for collapsing movement from a straightened position toward either one of two buckled positions, said breechblock being respectively open and closed when said toggle spring linkage is in one or the other of said buckled positions.

3. In a gun provided with a breechblock reciprocably slideable between closed and open positions, a breechblock operating crankshaft journaled in the breech end of the gun, a toggle joint translating oscillatory crankshaft movement into reciprocatory breechblock movement between positions wherein said breechblock is opened and closed respectively, said toggle joint including a lever arm fixed on said crankshaft for swinging movement of its free end portion, and a link pivoted at one end to the swinging end portion of said lever arm and at its opposite end to the breechblock, said toggle joint being adapted to collapse upon movement of said breechblock into its open position through rotation of said crankshaft in one direction, said toggle joint being swingable, through rotation of said crankshaft in an opposite direction, past a straightened position to a slightly buckled position wherein said breechblock is closed, and toggle spring linkage biased for collapsing movement from a straightened position toward either one of two buckled positions, said toggle spring linkage including a lever arm fixed on said crankshaft for swinging movement of its free end portion, a link including relatively axially movable cylinder and rod portions one of said link portions being pivotally connected to the swinging end of the lever arm of said toggle spring linkage, pivot means connecting the other of said link portions to the breech end of the gun, and an expansion coil spring encircling said rod portion within said cylinder to urge the cylinder and rod portions of said link into axially extended relation for lengthening said link, the lengths of the lever arm and link of said toggle spring linkage in said axially extending relation being greater than the distance between said pivot means and said crankshaft whereby said spring urges said

axially extended relation being greater than the distance between said pivot means and said crankshaft whereby said spring urges said toggle spring linkage into one of said two buckled positions at opposite sides of its straightened position, said breechblock being respectively open and closed when said toggle spring linkage is in one or the other of said buckled positions.

4. In a gun provided with a breechblock reciprocably slideable between closed and open positions, a breechblock operating crankshaft journaled in the breech end of the gun, a toggle joint translating oscillatory crankshaft movement into reciprocatory breechblock movement between positions wherein said breechblock is opened and closed respectively, said toggle joint including a lever arm fixed on said crankshaft for swinging movement of its free end portion, an abutment positioned on said toggle joint for engagement upon closing of said breechblock, and a link pivoted at one end to the swinging end portion of said lever arm and at its opposite end to the breechblock, said toggle joint being collapsible upon movement of said breechblock into its open position through rotation of said crankshaft in one direction, said toggle joint being swingable through rotation of said crankshaft in an opposite direction, past a straightened position to a slightly buckled position predetermined by said abutment when the breechblock is closed, and toggle spring linkage biased for collapsing movement from a straightened position toward either one of two buckled positions, said toggle spring linkage including a lever arm fixed on said crankshaft for swinging movement of its free end portion, a link including relatively axially movable cylinder and rod portions, one of said link portions being pivotally connected to the swinging end of the lever arm of said toggle spring linkage, pivot means connecting the other of said link portions to the breech end of the gun, and an expansion coil spring encircling said rod portion within said cylinder to urge the cylinder and rod portions of said link into axially extended relation for lengthening said link, the lengths of the lever arm and link of said toggle spring linkage in said axially extending relation being greater than the distance between said pivot means and said crankshaft whereby said spring urges said toggle spring linkage into one of said two buckled positions at opposite sides of its straightened position, said breechblock being respectively open and closed when said toggle spring linkage is in one or the other of said buckled positions.
